UNITED STATES PATENT OFFICE.

LUTHER D. LOVEKIN, OF PHILADELPHIA, PENNSYLVANIA.

SURFACE CONDENSER.

1,264,195.

Specification of Letters Patent. Patented Apr. 30, 1918.

Application filed March 6, 1917. Serial No. 152,734.

To all whom it may concern:

Be it known that I, LUTHER D. LOVEKIN, a citizen of the United States, residing in the city and county of Philadelphia, in the State of Pennsylvania, have invented certain new and useful Improvements in Surface Condensers, of which the following is a true and exact description, reference being had to the accompanying drawings, which form a part thereof.

The general object of my present invention is to provide a surface condenser which will be efficient in operation, and will have a relatively large capacity per unit of volume and weight, and will deliver condensate at a relatively high temperature. My improved condenser is of especial utility for use in units of relatively large capacity, and its compactness, coupled with certain operating advantages hereinafter explained, especially adapts it for use on battleships and in other places where the normal load is much smaller than the maximum load which must occasionally be handled for considerable periods of time.

The various features of novelty which characterize my invention are pointed out with particularity in the claims annexed to and forming a part of this specification. For a better understanding of the invention, however, and of its advantages, and of specific objects obtained with its use reference should be had to the accompanying drawings and descriptive matter in which I have illustrated preferred embodiments of my invention.

Of the drawings:

Figure 1 is a longitudinal section taken on the line 1—1 of Fig. 2; Figure 2 is a transverse section taken on the line 2—2 of Fig. 1; and

Fig. 3 is a transverse section of a modified construction.

In the drawings and referring first to the construction illustrated in Figs. 1 and 2, A represents the shell or casing body of the condenser. As shown, the shell A is cylindrical and is provided with two upper steam inlets A' and an outlet A² at its bottom for water of condensation and air. The ends of the condensing space are closed by the usual tube sheets B against the outer ends of which are secured the chambered end members or heads C and D as is usual.

The head C is provided with a bottom inlet C', and an upper outlet C² for the cooling water. The inlet C' opens into an inlet chamber C³ and is separated from the outlet chamber C⁴ by a partition member C⁵, the shape of which is shown in Fig. 2. The end member D is formed with a single water chamber D'. The horizontal condensing tubes E and e, extending through the condensing space are connected to the tube sheets in the usual manner, and connect the water chambers C³ and C⁴ of the end member C to the water chamber D' in the end member D.

The condensing space is divided into two zones or sections, a primary zone traversed by the tubes E and a secondary zone traversed by the tubes e. The tubes e traversing the secondary condensing zone or section are arranged in a stack or nest rising from the bottom of the condenser shell and having vertical sides and an oppositely tapered or wedge-shaped upper end. The latter is located some distance below the top of the condensing space and is covered by a roof or rain-plate f' in the form of an inverted trough.

Advantageously, as shown, rain-plates f parallel to the oppositely inclined sides of the roof member f', are arranged at intervals in the stack of tubes e. The baffles or rain-plates f are, in the construction illustrated in the Figs. 1 and 2, in contact at their upper edges with a pair of vertical perforated plates G. The latter are spaced apart and thus provide between them a vertical air channel g in communication with the condensing space from the top to the bottom of the stack of tubes e and from one end of the condensing space to the other through distributed apertures G'.

The plates G are connected at their lower ends through oppositely tapered plates G² to the horizontal plate G³ which closes the lower end of the air channel and is located somewhat above the bottom of the condenser shell. A tubular part or pipe section G⁴ leads to the condenser outlet A² from a port opening through the plate G³ into the lower end of the air channel g. The lower end of the pipe section G⁴ dips into the annular channel or trough A³ provided at the margin of the condenser outlet A², thus forming a water seal through which water

of condensation may freely flow, while compelling air escaping from the condensing space to flow through the air channel g and conduit G^4 in passing to the condenser outlet A^2 . It will be understood that I use the term "air" as it is ordinarily employed in this art, to designate not only atmospheric air but all uncondensed vapors and gases to be withdrawn from the condensing space.

10 Any suitable means may be employed for withdrawing the air and condensate from the condenser. As shown the outlet connection A^9 , secured to the condenser shell and communicating with the outlet A^2 , is formed with a tubular part A^4 which extends through but does not fill the conduit G^4 and terminates at its lower end in an outlet A^5 . A baffle G^5 prevents any condensate forming in or falling through the air channel g from falling directly into the upper end of the tubular part A^4 . The connection A^9 is also formed with a channel A^6 communicating at its upper side with the annular space between the conduit G^4 and the tubular part A^4 , and having two outlets A^8 and A^7 only one of which is intended to be in use at any one time. In one contemplated mode of use, the outlet A^4 is connected to any suitable dry air ejector and the outlet A^7 is connected to a condensate pump. In this use of the apparatus the outlet A^8 is closed. In another contemplated mode of use of the apparatus the outlets A^5 and A^7 are both closed and the outlet A^8 is connected to a wet air pump employed to remove both the condensate and air from the condensing space. With either mode of use the water seal provided by the extension of the tubular part G^4 into the trough A^3 compels the air escaping from the condenser to pass through the air channel g and part G^4 .

The primary condensing zone traversed by the tubes E , in the preferred construction illustrated, is U-shaped in cross section and extends over and down at the sides of the secondary zone from which it is separated by the vertical water passages H at the sides of the secondary zone, and by the inclined channels or spaces H' lying immediately above the roof plate f' . Inclined baffles or rain-plates F are suitably disposed among the tubes E to provide short separate paths of flow across the tubes E for the steam entering the condenser through the inlets A' , and thus properly distribute the steam through the primary condensing space, while each may carry the water of condensation formed in the group of tubes above it into the water passages H and H' . To prevent the water of condensation from forming continuous films or water veils in the water channels H , which would interfere with the free flow of air and uncondensed steam across the water channels H' from the primary condensing zone into the sec-

ondary condensing zone, short gutter pieces or barriers f'' , each shown as of angle bar section, are secured to the lower edges of the roof plate f' , the rain-plates f , and the rain-plates F , having their lower edges at the 70 sides of the secondary condenser zone. These gutter or barrier parts cause the water of condensation to flow off of the rain-plates to which they are attached in a series of horizontally displaced streams instead of in 75 continuous films.

The partition member C^6 separating the inlet and outlet chambers C^3 and C^4 in the end member C is shaped to register with the inclined water passages H' and the upper 80 portions of the vertical water passages H . The partition member C^5 terminates at each end however, in a horizontal portion extending to the periphery of the condenser's shell. Preferably never less, and usually 85 more than half of the condensing space is comprised in the primary condensing section traversed by the tubes E . The primary group of tubes E are spaced away from the condenser shell to provide a steam inlet 90 space in two sections and in communication with each steam inlet A' , which together, practically cover the convex outer side of the group of tubes E .

In operation, all, or the major portion of 95 the steam passing into the condenser through the inlets A' is condensed in the primary condensing zone. The uncondensed residue passes from the inner surface of the primary zone into the secondary zone wherein its 100 steam content, if any, is condensed, and its air content is cooled. The cooled air then passes into the air channels g between the plates G .

With the described construction each condensing zone provides a relatively short, but very wide path for the steam. This is conducive to efficient operation, maximum effectiveness and a minimum pressure loss between the condenser steam inlets A' and the 105 outlet A^2 . The capacity and efficiency of the apparatus is favorably affected moreover, by the protection to the lower tubes E and e from the drip from upper tubes which is furnished by the rain-plates F and f . Said 110 plates by dividing up the condensing zones into a plurality of sections, each extending from the outer to the inner surface of the corresponding zone, also contribute to a desirable distribution of the steam and to the 115 avoidance of stagnant collections of air in any portion of either zone. It is also a matter of some practical advantage that the various structural and operative features referred to may be obtained in a condenser of 120 cylindrical outline.

The condensate formed in the primary condensing zone will pass to the outlet A^2 of the condenser without coming in contact with the tubes e of the secondary condens- 130

ing zone and in consequence will be delivered substantially hotter than would be possible if the condensate were subjected to the direct cooling action of the tubes of the secondary zone. The condensate formed in the secondary zone will be colder than that formed in the primary zone, but when the two condensates are mixed the cooling effect on the mixture of the condensate from 5 the secondary zone will be greatly minimized, under normal conditions of operation, by the small volume of the condensate from the secondary zone as compared with the condensate formed in the primary zone. 10 This is particularly true with condensers used on battleships and under like conditions where the ordinary load is not more than one-half or so of the maximum load which the condenser is designed to carry. 15 Under such conditions of use, at normal load, all but a small fraction of the steam will be condensed in the primary zone, and the condensate may be withdrawn from the condenser at a temperature but little below 20 the theoretical maximum possible with the vacuum existing in the condenser.

It is to be noted that the effect of operating the condenser under such conditions that all or practically all condensation occurs in the primary zone, is to increase the condensing capacity of the primary zone in comparison to its capacity when a substantial amount of steam is being condensed in the secondary zone. This is because of the 35 fact that when no condensation occurs in the secondary zone, the cooling water is admitted to the tubes E at practically the same temperature at which it is admitted to the condenser. Under these conditions the 40 condenser operates, in effect, practically the same as a single flow condenser.

In Fig. 3 I have illustrated a simple modification of the preferred form of apparatus illustrated in Figs. 1 and 2. In Fig. 3 the condenser shell AA is provided with a single steam inlet A¹⁰, but a septum F¹⁰ insures a substantially equal division of the entering steam, one-half passing to the right hand upper quadrant and the other half to 45 the left hand upper quadrant of the condensing space, and passing into said condensing space through the periphery of the corresponding primary zone or section traversed by the tubes EA. The primary condensing zone in Fig. 3 is divided up into sections by baffles FA corresponding in arrangement generally to the baffles first described. The secondary condensing zone in 50 Fig. 3 is smaller relatively to the primary condensing zone than in Figs. 1 and 2; the tubes ea traversing this zone are divided into but two sections, separated by a central vertical air channel. The air box GA of Fig. 3 communicating with the air outlet A² 55 is shown as open at its upper edge only. A

baffle f¹⁰ shown as located about midway between the upper and lower edges of the air channel, prevents condensate from falling into the open upper edge of the air box GA. The secondary condensing zone is covered by a rain-plate fa' corresponding generally to the rain-plate or roof f', of Figs. 1 and 2. The cooling water partition C⁵⁰ in Fig. 3, comprises a central portion corresponding in shape to, and lying above the 75 plate fa', and horizontal portions passing to the periphery of the condensing shell from the level of the lower edges of the baffle fa'. 70

While in accordance with the provisions of the statutes I have illustrated and described the best forms of my invention now known to me, it will be apparent to those skilled in the art that many changes may be made in the form of the apparatus disclosed without departing from the spirit of 80 my invention, and that certain features of my invention may sometimes be used to advantage without a corresponding use of other features, and I do not wish the claims hereinafter to be made to be limited to the 85 particular forms of apparatus disclosed more than is made necessary by the prior state of the art.

Having now described my invention, what I claim as new and desire to secure by Letters Patent, is:—

1. In a surface condenser, the combination with a shell inclosing a condensing space, of horizontal condensing tubes traversing said space and divided into a secondary condensing group or stack rising from the bottom of said space, and a primary condensing group which extends over the secondary group and down at each side of the latter, and means for preventing water of condensation formed in the portion of the condensing space traversed by the tubes of the primary group from flowing into the portion of the condensing space traversed by the secondary group of tubes. 100

2. In a surface condenser, the combination with a shell inclosing a condensing space and provided with separated steam inlet and air outlet ports for said space, of cooling fluid tubes traversing said space and arranged to form two condensing zones or groups extending across the gas path between said inlet and outlet ports and separated from one another by vertical spaces, and means for causing water of condensation formed in 105 each condensing zone to flow into said vertical spaces.

3. In a surface condenser, the combination with a shell inclosing a condensing space, of horizontal condensing tubes traversing said space and divided into a secondary condensing group rising from the bottom of said space, and a primary condensing group which extends over the secondary group and down at each side of the latter, said groups 115 120 125 130

of tubes being spaced apart to provide vertical spaces at the sides of secondary group, and a roof over said secondary group to divert water of condensation forming in the 5 portion of the condensing space above it into said vertical spaces.

4. In a surface condenser, the combination with a shell inclosing a condensing space and having an outlet at its bottom for water 10 of condensation, of horizontal condensing tubes traversing said space and divided into a secondary condensing group or stack of tubes rising from the bottom of said space, and a primary condensing group which extends 15 over the secondary group and down at each side of the latter, means for diverting water of condensation formed in the portion of the condensing space above the secondary group of tubes to the sides of said 20 group, and air discharging means including an air channel opening to said condensing space in the portion thereof traversed by said secondary group of tubes.

5. In a surface condenser, the combination 25 with a shell inclosing a condensing space and having upper steam inlet and lower water of condensation outlet ports for said space, of horizontal condensing tubes traversing said space and divided into a secondary 30 condensing group or stack of tubes rising from the bottom of said group, and a primary condensing group which extends over the secondary group and down at each side of the latter said groups of tubes being 35 spaced apart to provide vertical spaces between the groups at the sides of said secondary group, and means for diverting water of condensation formed in the condensing space into said vertical spaces and causing it 40 to flow downward through the latter in horizontally displaced streams.

6. In a surface condenser, the combination with a shell inclosing a condensing space and having upper steam inlet and lower 45 water of condensation outlet ports for said space, of horizontal condensing tubes traversing said space and divided into a secondary condensing group or stack of tubes rising from the bottom of said group, and a primary 50 condensing group which extends over the secondary group and down at each side of the latter, said groups of tubes being spaced apart to provide vertical spaces between the groups at the sides of said secondary 55 group, and means for diverting water of condensation formed in the portions of condensing space traversed by the two groups into said vertical spaces and causing it to flow downward through said spaces in 60 horizontally displaced streams.

7. In a surface condenser, the combination with a horizontal cylindrical shell inclosing a condensing space and having upper steam inlet and lower water of condensation outlet 65 ports, of horizontal condensing tubes trav-

ersing said space and divided into a secondary condensing group or stack of tubes rising from the bottom of said space, and a primary condensing group which extends over the secondary group and down at each side 70 of the latter and is spaced away from the shell to provide a steam inlet space substantially covering the outer or convex side of said group of primary condensing tubes, means for diverting water of condensation 75 formed in the portion of the condensing space above said secondary group of tubes to the sides of the latter, and air discharging means including an air channel opening to said condensing space in the portion thereof 80 traversed by said secondary group of tubes.

8. In a surface condenser, the combination with a horizontal cylindrical shell inclosing a condensing space and having upper steam inlet and lower water of condensation outlet 85 ports for said space, of horizontal condensing tubes traversing said space and divided into a secondary condensing group or stack of tubes rising from the bottom of said space, and a primary condensing group which extends over the secondary group and down at each side 90 of the latter, but is spaced away from the latter to provide vertical water spaces at the sides of the latter, and is spaced away from the shell to provide a steam inlet space substantially covering the convex outer side of said primary group of tubes, rain or baffle plates arranged among the primary group of tubes to divert water of condensation 95 formed in the space traversed by said group into said vertical water spaces and to provide a plurality of parallel paths of flow of approximately the same length from said steam inlet space to the other side of said secondary group of tubes, and air discharging 100 means including an air channel opening to said condensing space within a portion thereof traversed by the said secondary group of tubes.

9. In a surface condenser, the combination with a shell inclosing a condensing space and provided with a lower outlet, of a nest of cooling fluid tubes traversing said space, means providing an air chamber opening within said nest of tubes, a conduit leading 110 from said air chamber to said outlet and means providing a water seal between said conduit and shell through which water of condensation may pass, while said seal compels air escaping from the condensing space 115 to flow to said outlet through said air channel and conduit.

10. In a surface condenser, the combination with a shell inclosing a condensing space and provided with a lower outlet, of a nest of cooling fluid tubes traversing said space, means providing an air chamber opening within said nest of tubes, a conduit leading 120 from said air chamber down to said outlet, means providing a water seal be- 125

tween said conduit and shell, through which water of condensation may pass while said seal compels air escaping from the condensing space to flow to said outlet through said 5 air chamber and conduit, and an air pipe extending up through the outlet into said conduit but not filling either said outlet or said conduit.

11. In a surface condenser, the combination 10 with a shell inclosing a condensing space and provided with a lower outlet from said space, of a nest of cooling fluid tubes traversing said space, means providing an air channel opening within said nest 15 of tubes, a conduit leading from said air channel down to said outlet, means providing a water seal between said conduit and shell through which water of condensation may pass while said seal compels air escap- 20 ing from the condensing space to flow to said outlet through said air chamber and conduit, and comprising a connection to said shell closing said outlet and formed with a chamber or passage into which said 25 conduit opens and which receives the over-flow from said seal with one or more outlets from said chamber, and comprising also a tubular portion extending up into but not

filling said conduit, and having an outlet external of said shell for the passage in said 30 tubular portion.

12. In a surface condenser, the combination 35 with a condenser body inclosing a condensing space and having upper steam inlet and lower water of condensation outlet ports for said space, and having water chambers at the ends of said space, of horizontal condensing tubes traversing said space and connecting the water chambers and divided into a secondary condensing group or stack 40 of tubes rising from the bottom of said space, and a primary condensing group which extends over the secondary group and down at each side of the latter, but is spaced away from the latter to provide ver- 45 tical water spaces at the sides of the latter, air discharging means including an air channel opening to said condensing space within a portion thereof traversed by the said secondary group of tubes, said body includ- 50 ing a baffle or partition dividing one of said water chambers into separate inlet and outlet compartments, said partition including vertical portions registering with said water spaces.

LUTHER D. LOVEKIN.
